DESIGN FOR WALL-PAPER.

SPECIFICATION forming part of Design No. 22,936, dated November 28, 1893.

Application filed October 14, 1893. Serial No. 488,185. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification.

The design consists of a series of ornamental stripes arranged vertically, and between 10 said stripes interlacing ribbons, and vines of flowers and leaves, running vertically in a wavy or serpentine-like manner as represented in the accompanying drawing. The ornamental stripes are formed of a series of 15 connected scrolls which form the edges of said stripes, and small diamond shaped ornaments and dots inclosed in a net work composed of fine diagonal lines extending across said stripes as shown.

The border or upper portion of the design 20 is formed of ornamental scrolls forming a diamond shaped panel filled with small diamond shaped ornaments and dots inclosed in a net work of fine diagonal lines as shown in the drawing, with ribbon festoons and sprays 25 of flowers and leaves on each side of said panels as shown.

What I claim is—

1. The design for wall paper herein shown and described.
2. In the design for wall paper, the border herein shown and described. 30

Witness my hand this 5th day of October, 1893.

CHARLES BOOZE.
